UNITED STATES PATENT OFFICE.

CHARLES T. PARRY, OF PHILADELPHIA, PENNSYLVANIA.

MACHINERY FOR GRINDING OR POLISHING CROSS-HEAD GUIDES.

SPECIFICATION forming part of Letters Patent No. 270,106, dated January 2, 1863.

Application filed November 6, 1882. (No model.)

To all whom it may concern:

Be it known that I, CHARLES T. PARRY, a citizen of the United States, and a resident of Philadelphia, Pennsylvania, have invented 5 certain Improvements in Machinery for Grinding or Polishing Cross-Head Guides, of which the following is a specification.

My invention consists of certain improvements in mechanism, fully described hereinafter, for quickly and truly facing, by grinding and polishing, the guides for the cross-heads of locomotive-engines.

In the accompanying drawings, Figure 1, Sheet 1, is a side view of my machine for 15 grinding or polishing locomotive-guides; Fig. 2, a plan view; Fig. 3, a vertical section on the line 1 2, Fig. 1; Fig. 4, Sheet 2, a perspective view of the machine; Fig. 5, a vertical section on the line 3 4 of part of the machine, drawn 20 to an enlarged scale; and Fig. 6, a section on the line 5 6, also drawn to an enlarged scale.

To guides on a frame, A, similar to that of an ordinary metal-planing machine is adapted 25 a bed-plate, B, which is caused to traverse to and fro on the frame by any suitable mechanism, a screw being in the present instance used in connection with driving-gear for this purpose.

To the bed-plate B are secured a series of 30 supporting-blocks, D, in the recessed portions of which is placed the guide W, the latter being secured by clamps d.

An extension, A', from one side of the frame A carries a head-stock, G, having bearings for 35 a spindle, H, to which are secured the pulley f for a driving-belt, and a lap-wheel, I, which is composed of the inner portion, i, of lead, and the portion m, of cast-iron, into which the lead is cast. The head-stock is adapted to 40 guides on a plate, F, which is pivoted at y to the extension A' of the frame, a screw-shaft, E, furnished with a suitable hand-wheel, n, serving to move the head-stock with its guides and to keep the lap-wheel up to its work. The 45 plate F and head-stock can be tilted on the pivot y, for a purpose explained hereinafter, the device for effecting this adjustment consisting in the present instance of a wedge or key, M, Fig. 1, interposed between the said 50 plate and a projection on the end of the extension A' of the frame, the wedge being controlled by a screw, p.

A link, q, is pivoted to the under side of the plate F, and through this link passes a lever, N, Fig. 6, which also passes through openings 55 in the extension of the frame to which the lever is pivoted at s. A nut adapted to a screw, t, is swiveled to the outer end of this lever, the screw being arranged to turn in a bracket on the frame, and being furnished 60 with a suitable handle.

The object of the above-described mechanism is to hold the plate F and its head-stock firmly in place after adjustment, this being accomplished by turning the screw t so as to depress the lever N and draw the plate down tight on the wedge.

The axis of the spindle H is not quite at right angles horizontally to the guides which the bed-plate traverses, so that the face of the 70 lap-wheel, instead of being parallel with the said guides, is at a slight angle in respect to the same; hence a limited portion only of the lap-wheel acts on the guide.

The guide W to be faced by the lap-wheel 75 is in the first instance placed on the blocks D so as to be parallel with the guides of the bed-plate, after which it is secured by the clamps d, and the mechanism for traversing the bed-plate is set in motion, the result being the accurate facing of the guide by the lap-wheel.

The object of the tilting adjustment of the plate F and head-stock is as follows: If on 80 adjusting the head-stock by means of the screw E prior to setting the machine in motion, so as to move the lap-wheel up to its place, it should be found that the face of the guide to be ground is not at right angles to that face which rests on the blocks—that is, if either top or bottom of the guide is out of line throughout its entire length, and would require unnecessary cutting or grinding to reduce it to the proper plane—I adjust the face of the lap-wheel by moving the plate F on its pivot until the said wheel is parallel with the face of the 90 guide, thereby obviating the necessity of blocking the latter up.

A reciprocating work-supporting bed has heretofore been combined with a reducing-wheel on a spindle carried by a frame which 100 could be so tilted as to alter the position of the face of the wheel in respect to the bed. This, therefore, I do not claim broadly; but

I claim as my invention—

1. The combination of the reciprocated bed B, adapted to guides on a frame, A, and the plate F, carrying the head-stock G, the spindle, and lap-wheel, and pivoted in front to the frame of the machine, with the screw t and intervening mechanism, whereby the said screw can be made to raise or lower the said pivoted plate at the rear, all substantially as set forth.
2. The combination, with the frame of the machine, of the pivoted plate F and its head-stock, and a wedge, M, interposed between the said plate and the frame of the machine, substantially as described.

3. The combination of the pivoted plate and wedge M with the link q, lever N, and screw t, having a nut swiveled to the lever, substantially as specified.

In testimony whereof I have signed my name to this specification in the presence of two subscribing witnesses.

CHAS. T. PARRY.
